JOHN B. O'HARA, OF DALLAS, TEXAS, ASSIGNOR TO DR. PEPPER COMPANY, OF DALLAS, TEXAS

DESIGN FOR A BOTTLE

Application filed July 15, 1929. Serial No. 32,059. Term of patent 14 years.

To all whom it may concern:

Be it known that I, JOHN B. O'HARA, a citizen of the United States, residing at Dallas, Dallas County, Texas, have invented a new, original, and ornamental Design for Bottles, of which the following is a specification, reference being had to the accompanying drawing, forming part thereof.

The Figures 1, 2 and 3 represent respectively opposite side views and a bottom view of the bottle illustrating my new design.

I claim:

The ornamental design for a bottle as shown.

JOHN B. O'HARA.
